(57) CLAIM

The ornamental design for a “socket for cutting material placed over a fastener,” as shown and described.

DESCRIPTION

FIG. 1 is a perspective view of a first embodiment of a wrench socket adapted for cutting through material placed over a fastener, showing my new design;

FIG. 2 is a top plan view thereof;

FIG. 3 is a side elevation view thereof, common to side elevation views from all sides, the socket having circular symmetry;

FIG. 4 is a bottom plan view thereof;

FIG. 5 is a perspective view of a second embodiment of the wrench socket of FIGS. 1-4 showing six small cutaway portions along a top hexagonal edge thereof;

FIG. 6 is a top plan view thereof;

FIG. 7 is a side elevation view thereof, common to side elevation views from all sides, the socket having circular symmetry; and,

FIG. 8 is a bottom plan view thereof.
